UNITED STATES PATENT OFFICE.

EDWIN HARRINGTON, OF MANCHESTER, NEW YORK.

HAY ELEVATOR AND CARRIER.

SPECIFICATION forming part of Letters Patent No. 257,161, dated May 2, 1882.

Application filed October 3, 1881. (No model.)

To all whom it may concern:

Be it known that I, EDWIN HARRINGTON, of Manchester, in the county of Ontario and State of New York, have invented certain Improvements in Hay Elevators and Carriers, of which the following is a specification.

My invention relates to hay elevators and carriers; and the improvements consist in a vertically-sliding brake and rope-clamping device controlled through the carrying-arms by the weight of the load; in stops for holding the apparatus in position on the track, and in other features and details hereinafter more fully explained.

15 In the accompanying drawings, Figure 1 represents a side elevation of my improved apparatus; Fig. 2, a similar view with the side of the shell or casing removed; Fig. 3, a top plan view of the carriage and track, one side 20 being broken away; and Fig. 4, a face or edge view of the brake and the rope-pulley.

A represents the shell or casing of the carriage, consisting of two side plates, *a* and *b*, supported and carried by arms or levers *B*, 25 pivoted between said plates, and furnished at their upper and outer ends with supporting and carrying wheels *c*, which travel upon beams or rails *C*, as shown.

D represents a vertically-moving brake and 30 rope-clamping device, formed with ribs *d* on its sides, which move in recesses or grooves *e* in the side plates, *a* *b*, and serve to guide the brake in its movements. The brake consists of an upright stem, the lower end of which is 35 extended laterally and serrated to more effectually hold the rope *E*, while the side ribs, *d*, are carried below the serrated portion to engage with lugs *f* on the sides of the rope wheel or pulley *F*. The stem or body of the brake 40 is slotted or formed with an opening, *g*, through which the overlapping ends of the carrying arms or levers *B* pass, as shown in Figs. 2 and 4. The weight of the carriage and its load being sustained by the arms or levers *B*, the latter 45 of course tend constantly to assume a vertical position, and in turning upon their pivots or journals throw down their inner or lower ends, which, being too long to withdraw from the opening *g*, force the brake and clamp down 50 before them toward the rope wheel or pulley *F*, located directly beneath.

From the above it will be seen that unless elevated and held up by special means the brake and clamp will descend and lock the wheel or pulley against rotation and the rope 55 against slipping.

For the purpose of releasing and withdrawing the brake and clamp when at the point for loading or unloading the brake-stem is furnished with laterally-projecting pins or lugs 60 *h*, which extend through slots *i* in the side plates of shell or casing and ride upon an inclined block or plate, *G*, secured to the inner face of the supporting beams or track *C*, one on each side of the carriage. These 65 blocks or plates are located at any desired point or points, and, besides having the inclined ends *j*, are furnished at the top and midway between their ends with a lug or projection, *k*, which serves as a stop to limit the movement 70 of the carriage.

I represent locking dogs or pawls pivoted within the shell or casing *A*, with their free ends toward each other. The inner or free ends of the pawls are formed with laterally-projecting ears *l*, which extend through openings *m* beyond the side plates, *a* *b*, as shown in Fig. 3. The ears *l* are beveled on their underfaces at the outer sides to ride over the lug or projection *k*, but have square or upright inner faces to abut 80 against said lug or projection. It will be seen that under this construction the carriage will be permitted to move readily until the ear *l* of one of the pawls rides over and drops in front of the projection *k*, when the upright face of 85 the ear of the opposite pawl will strike the lug or projection and prevent further movement in that direction, and the first pawl will prevent a backward movement. The carriage is thus held firmly in place at the desired point, 90 the lug and plate *G* being, as above stated, placed at the point of loading or unloading. The lug or projection *k* being at the middle of the plate or block *G*, the carriage is locked at the same time that the brake and clamp are 95 withdrawn. Hence the load may be raised or lowered, as desired, while the carriage remains stationary. Each pawl *l* is connected by a link, *n*, with a depending trip or yoke, *J*, through the ring *o* of each of which the hoisting-rope *E* 100 passes, as indicated in Figs. 1 and 2. Each link is guided by lugs or projections on its sides pass-

ing through or into slots in the side plates, *a* and *b*. The yoke or trip through which the rope passes down to the load hangs downward in a substantially vertical position, as shown, 5 and as the grappling device is drawn up it comes into contact with the ring or yoke of the trip and causes the same to rise and elevate the pawl or dog *I*, with which it is connected, thereby allowing the carriage to ride 10 from the block or plate *G* and permitting the brake and clamp to be thrown into action.

It will be observed that under the above construction the apparatus is capable of being moved and used without change in either direction at will. 15

In practice the plates *a* and *b* may be formed with openings or recesses to receive journals formed directly upon the arms or levers *B* and dogs *I*, the plates being tied together by shoul- 20 dered bolts *P* or by bolts provided with encircling sleeves or collars to separate and hold the plates apart; or bolts may be employed as the pivots of said parts.

The apparatus constructed as above set forth 25 is simple, cheap, strong, and efficient.

I am aware that hay-elevators have hitherto been constructed or proposed in which the carrying-arms were pivoted to each other and one of the arms provided with a brake and rope- 30 clamp to act upon the wheel and rope carried by the other arm. I am not, however, aware that anyone has hitherto provided a hay elevator and carrier with a vertically-sliding brake adapted to act in the same manner, 35 whether the carrier be moved in one or the other direction without changing its position in relation to the track—that is to say, with-

out turning it end for end—and without requiring the withdrawal of the rope and adjustment of the brake or of the rope-clamp. By 40 my improved construction I am enabled to work in either direction without alteration or adjustment of any kind.

Having thus described my invention, what I claim is— 45

1. The herein-described hay elevator and carrier, consisting of shell *A*, pivoted arms *B*, pulley *F*, brake *D*, dogs *I*, and trips or yokes *J*, combined and operating as set forth.

2. In a hay elevator and carrier, the combination of the body *A*, pulley *F*, arms *B*, and vertically-sliding brake *D*, controlled by said arms, substantially as set forth. 50

3. In a hay elevator and carrier, the combination of a pulley, a vertically-sliding brake, and pivoted sustaining arms extending through the body of the brake and serving to apply the weight of the carriage and load thereto, substantially in the manner explained. 55

4. In combination with the grooved plates *a* and *b* and pulley *F*, the brake *D*, having ribs to fit the grooves of the plates, as and for the purpose set forth.

5. In combination with the rope-pulley having lugs on its sides, the combined brake and clamp *D*, arranged to slide vertically in the shell or casing, substantially as shown. 60

6. The vertically-sliding brake and clamp *D*, provided with laterally-projecting lugs or pins to engage with a fixed incline, as described.

EDWIN HARRINGTON.
